A. M. WILLARD

SEAL PRESS

Original Filed July 2, 1923

Patented Feb. 14, 1928.

1,658,823

UNITED STATES PATENT OFFICE.

ARTHUR M. WILLARD, OF CHICAGO, ILLINOIS.

SEAL PRESS.

Application filed July 2, 1923, Serial No. 648,910. Renewed July 11, 1927.

This invention relates to presses through means of which paper or other material may be embossed between a pair of counterpart dies, and has for its object to provide 5 an improved construction of the frame or mounting for the relatively movable members of such a press.

It has heretofore been proposed to make the frame of a seal press out of a blank 10 of plate metal, inversely arched or bent upon itself in a manner to provide a connecting web at bottom, and two cheeks upstanding therefrom, slotted longitudinally to provide a paper receiving recess and jaws above and 15 below the recess; the jaws being spaced apart to receive the parts that carry the mating dies and cam lever. But in utilizing this form of frame, in spite of the edgewise presentation of the plate-like cheeks to the stresses 20 of embossing pressure and notwithstanding the presence of the strut-like web at the bottom, there has been found to be sufficient spring in the lower jaw or bed to impair registry of the dies; moreover, this method of 25 supporting the lower die upon the bed has not been satisfactory.

According to the present invention, a bed plate is mounted upon and between the cheek plates that form the lower jaw by anchoring 30 it immovably at its respective ends so that it constitutes an additional trussing member, extending in the same general direction as the bottom web, but spaced above the latter so that while the bottom web acts 35 as a compression member under the vertical deflecting stresses of embossing, the bed plate above it acts as tension member and greatly stiffens the whole structure; and then, in order to properly sustain the bed 40 plate vertically, it is given a form that adapts the forward end of the plate to rest upon and to be sustained by the cheek plates of the bed portion of the frame, and to abut rearwardly against shoulders formed 45 on said cheek plates, while the remainder of the bed plate, extending rearwardly and snugly fitting between the cheek plates, has its rear end rigidly anchored by means of a transverse pin which draws the bed plates 50 rigidly to the rear. The front end of the plate is anchored and locked against relative movement in any direction by its said shoulders and by riveting lugs rising from the seating edges of the lower jaw or bed.

In order that the present invention may

be fully understood, the preferred embodiment thereof is illustrated in the accompanying drawing, in which—

Figure 1 is a vertical longitudinal section of a press embodying the new frame construction and provided with a supporting base.

Figure 2 is a rear end elevation of the same.

Figure 3 is a section of the same on the line 3×—3× of Figure 1.

Figure 4 is a front elevation of the press shown in Figures 1, 2, and 3, with the base in section; and

Figure 5 is a side elevation of a press, 70 the construction of which is identical with that shown in Figures 1 to 4, except that the supporting base is omitted and the bed is extended rearwardly to provide a hand hold.

1 represents a frame member formed of a 75 plate metal blank folded along its longitudinal middle portion to provide two upstanding spaced cheeks, portions of the blank being slotted to subdivide the cheeks into bed portion 1^a and jaw portions 1^b. 2 represents a 80 bed plate fitted between the bed cheek portions 1^a, as shown more clearly in Figure 3, and having an enlarged forward end 2^a providing a table to receive the lower fixed embossing die, and of such form as will 85 adapt it to rest vertically upon the seat portions 1^c of the bed cheeks 1^a; the enlarged front end being offset from the longitudinal body portion of the bed plate in a manner to provide rearwardly presented shoulders 2^b 90 that abut rearwardly against shoulders 1^c of the bed cheeks, with an undercut fit if desired; and the main body of the bed plate being fitted snugly between the bed cheeks and extended rearwardly to a pin 3 which 95 not only draws the cheeks firmly against the plate 2 and unites the cheek plates and the bed plate laterally as a rigid braced structure, but also firmly anchors the plate against longitudinal movement at a point in 100 rear of the springing point of the jaws and thereby trusses the bed, makes it very much more rigid, and maintains better registry between the dies. As a further 105 means for firmly uniting the forward end of the bed plate to the bed cheeks of the frame, the cheeks are stamped with a pair of riveting lugs 1^d upstanding from the seating edges 1^e of the cheek portions, and passing through and headed in the bed plate in a 110

manner to firmly resist relative movement between the plate and the bed in any direction, and especially in the direction of the length of the plate, so that the plate can act as a tension member or strut in trussing the lower jaw or bed under the embossing pressure as explained.

To receive the pin 3, the rear end of the plate 2 is folded to provide an eye 2^c and the folded end 2^d extended to provide a reinforced table upon which to anchor the plate spring 5 which carries the movable embossing member 4, the rear end of which is rigidly secured to the said reinforced bed plate 2 by means of screw 6 which passes through said spring and through the two-fold thickness of the bed plate. A controlling lever 7 is fulcrumed in the frame at 8 in the usual manner, and carries the known arrangement of camming roller 9 coating with the anvil 10 of the movable die member 4.

A die press constructed as above described may be designed as a table press by providing it with a base 11 suitably secured thereto, as, for instance, by rivets 12 passing through the base and through the connecting web 1^e of the frame, as shown in Figures 1 to 4; or the frame 1 otherwise constructed as described in connection with Figures 1 to 4, may be provided with an extension 1^f that adapts it to serve as a hand hold, thereby adapting the press to serve as a so-called hand press.

35 I claim:

1. In a seal press, a frame comprising spaced cheek plates forming upper and lower jaws, and a bed plate immovably anchored at its ends to said cheek plates and resisting bending of said cheek plates in vertical planes.

40 2. In a seal press, a frame, comprising spaced cheek plates forming upper and lower jaws, a bed plate immovably anchored at its ends to said cheek plates and resisting bending of said cheek plates in vertical planes, and a movable die carrying member mounted on said bed plate.

45 3. In a seal press, a frame, comprising spaced cheek plates forming upper and lower jaws, a bed plate immovably anchored at its ends to said cheek plates and resisting bending of said cheek plates in vertical planes, and a movable die carrying member mounted on the rear end of said bed plate and extending forwardly to present its die over the forward end thereof.

50 4. In a seal press, a frame comprising spaced cheek plates united by a connecting web in a plane extending longitudinally and transversely of said cheek and thereby adapted to receive stresses of longitudinal compression from vertical bending stresses in the cheeks, and a bed plate in a transverse plane spaced from the plane of the

55 web firmly anchored at its ends on said cheeks, and receiving stresses of tension from said bending stresses.

5. In a seal press, a frame comprising a plate metal blank inversely arched to provide a longitudinally extending bottom web and two spaced cheek plates upstanding therefrom, a bed plate extending substantially parallel with but spaced above said web, fitting between the cheek plates and having its front and rear ends immovably anchored to said cheek plates, a lower die carried on the forward end of said bed plate, a movable die, and a carrier for said movable die secured at its rear end to said bed plate and extending forward thereover and presenting its die over the said lower die.

6. In a seal press, a frame comprising a plate metal blank inversely arched to provide a longitudinally extending bottom web and two spaced cheek plates upstanding therefrom, a bed plate extending substantially parallel with but spaced above said web, fitting between the cheek plates and having its front and rear ends immovably anchored to said cheek plates, a lower die carried on the forward end of said bed plate, a movable die, and a carrier for said movable die secured at its rear end to the rear end of and near the anchorage of said bed plate and extending forward thereover and presenting its die over the said lower die.

7. In a seal press, a frame comprising spaced cheeks, a bed plate fitted snugly between the cheeks and provided with an enlarged forward end through which it rests vertically upon front ends of the cheeks, and a pin passing through the cheeks, engaging the rear end of the bed plate, and drawing the cheeks together upon and holding the bed plate immovably with relation to the frame.

8. In a seal press, a frame comprising spaced cheeks, a bed plate fitted between the cheeks and provided with an enlarged forward end through which it rests vertically upon front ends of the cheeks, and a pin passing through the cheeks, engaging the rear end of the bed plate, and holding the bed plate immovably with relation to the frame; said front ends of the cheeks being vertically recessed to provide shoulders against which the enlarged forward end of the bed plate rearwardly abuts.

9. In a seal press, a frame comprising spaced cheek members, a bed plate fitted between the cheek members and provided with an enlarged forward end through which it rests vertically upon front ends of the cheek members, and a pin passing through the cheek members, engaging the rear end of the bed plate, and holding the bed plate immovably with relation to the frame; said front ends of the cheek members being vertically recessed to provide shoulders against

which the enlarged forward end of the bed plate rearwardly abuts; and said shoulders being undercut to engage said forward end of the bed plate vertically and prevent its upward displacement.

10. In a seal press, a frame comprising spaced cheek members, a bed plate fitted between the cheek members provided with an enlarged forward end through which it rests vertically upon the front ends of the cheek members, and a pin passing through the cheek members, engaging the rear end of the bed plate, and holding the bed plate immovably with relation to the frame; the rear end of the bed plate being folded upon itself to embrace the securing pin and provide a two-fold anchoring table for a movable die member; and there being firmly secured to said table a plate spring adapted 20 to carry said movable die member.

11. In a seal press, a frame comprising spaced cheek members, and a separately formed bed plate fitted between said cheek members and engaged therewith against

movement relatively thereto in forward, 25 rearward, upward, downward, and sidewise directions.

12. In a seal press, a frame comprising spaced cheek members, and a separately formed bed plate having an enlarged forward head interengaged with the forward portion of the cheek members against movement relatively thereto downwardly, upwardly, and rearwardly, and having a body portion extending rearwardly from said head portion, fitting snugly between said cheek members, thereby holding the head against lateral movement, and having its rear end firmly anchored to said cheek members to resist forward displacement of the bed plate; 40 there being anchored upon said rear end of the bed plate a separately formed plate spring adapted to carry an embossing member.

Signed at Chicago, Illinois, this 14th day 45 of June, 1923.

ARTHUR M. WILLARD.
